WITNESS:

C. J. Jackson,
INVENTOR
BY *Nietor J. Evans,*

INVENTOR

UNITED STATES PATENT OFFICE.

CARL JOHAN JACKSON, OF SUPERIOR, WISCONSIN.

SCREEN.

Application filed December 3, 1924. Serial No. 753,724.

To all whom it may concern:

Be it known that I, CARL J. JACKSON, a subject of the Kingdom of Norway, residing at Superior, in the county of Douglas 5 and State of Wisconsin, have invented new and useful Improvements in Screens, of which the following is a specification.

This invention relates to improvements in screens and contemplates the provision of 10 a novel form of frame which is subdivided into a window and screen portion, the screen portion being of the usual and ordinary type, but the novel portion of the device resides in the lower portion, that is the window 15 portion, which has layers of glass portions for letting out flies or other insects which frequently infest houses.

A further object is in the window portion whereby flies or the like may walk between 20 the sections of glass positioned therein but owing to the peculiar habit of insects they will not be able to enter between the sections of glass in order that they may enter the house.

25 With the above and other objects and advantages in view, the invention further includes the following novel features and details of construction; to be hereinafter more fully described, illustrated in the accompanying drawings, and pointed out in the appended claim.

In the drawings:

Figure 1 is a front elevation of a window frame showing the screen positioned therein.

35 Figure 2 is a front elevation of the screen per se.

Figure 3 is a transverse section taken on line 3—3 of Figure 1, and through the window portion.

40 Figure 4 is a longitudinal section taken through a portion of the screen and window portion respectively.

Referring to the drawings in detail, wherein like characters of reference denote corresponding parts, the reference character 45 10 indicates generally a window frame into which the present invention is positioned, which is clearly shown in Figure 1 for purposes of illustration only.

50 In the present invention, I provide a very common and ordinary type of screen frame which has longitudinal side members 11,

transverse or horizontal end sections 12, and said frame is further sub-divided into screen and window portions 13 and 14 through the 55 medium of a cross member 15 and extending transversely of the frame adjacent the long end thereof. The screen portion merely includes a strip of screen wire lying flush against the side and end walls of the frame 60 and held thereon through the medium of molding strips 16 which extend around the inner periphery of the frame. It is to be understood that the screen portion does not form the entire subject matter of the present invention, but is merely used in combination with the present invention.

Referring to the window portion 14, I provide a pair of glass panels 17 which are spaced apart an appreciable distance intermediate of the width of the frame in order to provide an exit 18 for the flies or other insects to pass through on the way out of the domicile. These panels 17 are seated within grooves 19 provided in the lower portion 75 of the frame whereby the glass and screen portions may be held to the frame by the same holding means 16. Positioned directly behind and upon the rear face of the frame is an auxiliary relatively narrow panel of 80 light material which is positioned directly behind the exit 18.

Owing to the peculiar habit of flies and other insects they cannot enter the exit 18 85 into the house but may only pass outwardly therefrom from the inside of the domicile.

Another and further object of the present invention which applicant deems necessary is owing to the fact that this screen may be kept in the window frame 10 the year 90 around, and be used as a ventilator owing to the fact that the lower portion of the window may be raised to the transversely extending member 15 in order to allow air to pass through the exit 18 and be deflected by the relatively narrow glass panel and transversely of the frame whereby a direct draft may not enter the room.

The invention is susceptible of various 100 changes in its form, proportion and minor details of construction, and the right is herein reserved to make such changes as properly fall within the scope of the appended claim.

Having thus described my invention, I claim:

A window screen exit of the character described comprising a frame member partitioned into screen and exit portions respectively, the exit portion including a pair of transparent panels secured in end to end relation within the frame and having their

inner edges arranged in spaced relation in providing an exit therebetween, and a relatively narrow transparent panel positioned directly behind the exit and in spaced relation thereto whereby an exit and window ventilator is provided.

In testimony whereof I affix my signature.

CARL JOHAN JACKSON.
